UNITED STATES PATENT OFFICE.

GEORGE HUNT AND CHARLES WILLIAM CAMPION, OF NOTTINGHAM, ENGLAND.

PRESS FOR FINISHING TUBULAR FABRICS.

Application filed February 24, 1925, Serial No. 11,250, and in Great Britain February 28, 1924.

This invention relates to improvements which are applicable to the presses employed for finishing fabrics, such for example as knitted webbing, and its object is to render 5 such presses automatic when dealing with tubular fabrics.

In the process of pressing tubular fabrics, a board of the necessary dimensions is employed, this board is disposed in the interior 10 of the fabric in order to extend it to the desired width, and the fabric is pressed on this board between the heated beds of a press, a short length at a time. After each length has been pressed, the board is moved 15 along the interior of the fabric, and the latter then re-adjusted in the press for pressing the next length, both of which processes have to be carried out by hand.

According to this invention, a board or 20 plate over which the fabric is fed, is disposed between the upper and lower beds of the press, this board or plate is supported and retained in position by means of rollers, and these rollers are positively rotated so 25 as to automatically feed the fabric forward over the board or plate. This feed is intermittent, and the process of pressing which is automatically effected, takes place whilst the fabric is at rest. In the preferred ar- 30 rangement, the tubular fabric stretching device described in British Patent No. 212,369, is used in conjunction with the fabric ex- tending board or plate described.

Referring to the accompanying drawings, 35 Figs. 1 and 1^a show a side elevation, and Figs. 2 and 2^a a plan of an automatic press for finishing tubular fabrics, constructed according to our invention.

Fig. 3 is a side view of the arrangement 40 for imparting intermittent motion to the fabric feeding mechanism.

Like letters indicate like parts throughout the drawings.

The press is preferably constructed with 45 a stationary upper bed A, and a movable lower bed B, and a board or plate C over which the tubular fabric is drawn and extended, is located between the two beds A and B, being supported on horizontal roll- 50 ers D D' disposed at the front and rear re- spectively of the lower bed B as shown. The normal position in which the board or plate C is held by the rollers D D' is clear of both beds, when the lower one B is in its 55 lower position, so that the feeding forward of the fabric, is not checked by frictional

contact at this time with either of the beds. When the lower bed B rises to press the fabric, the plate or board C is raised and carried up to the upper bed A, and thus 60 effects the pressing of the upper and lower layers of fabric between which the board or plate is located. The upper bed A is mounted on vertical pillars E on the main framing P and is held down to its work by 65 springs E' on said pillars. The pressure put upon the work can thus be regulated by these springs, and provision is made for adjusting them from time to time as required. 70

The fabric extending plate or board C, which must be of the correct width for the fabric under treatment, is as shown, prevented from moving forward by connecting its fore end to the free ends of the fabric 75 extending arms F of the tubular fabric stretching device Z described in the British Patent No. 212,369, hereinbefore cited. As shown the fore end of the board or plate C is formed with side notches C', and the 80 free ends of the arms F are provided with studs F' to engage in said notches. The plate or board C may however be prevented from moving longitudinally by any other approved means. The rear end of the board or plate C is prevented from moving trans- 85 versely by means of two vertical rollers G, between which it is located.

The horizontal plate supporting rollers D, D' and the vertical rollers G, are rotated 90 so as to feed the fabric on the board or plate C forward at the desired rate, and in order that fabric extending boards or plates C of different widths may be employed as is re- 95 quired, the vertical rollers G are carried so that they can be transversely adjusted, without disconnecting them from the driving mechanism.

As shown in the drawings, the rollers G are carried by brackets G' which are mount- 100 ed and are adjustable on two transverse shafts H and H', the former one H of which is driven whilst the other one H' is fixed. Bevel wheels J are splined to the shaft H, and these wheels engage with corresponding 105 wheels on the axes of and drive the vertical rollers G. The shafts H and H' are mount- ed in bearing brackets P' secured to the framing P, and the former H is driven as is hereinafter described. 110

The lower movable bed B of the press which is mounted on the same vertical pillars

E which carry the upper bed A, is preferably actuated by means of four cams L, disposed in pairs on two transverse cam shafts M M' carried in bearings on its underside in the main framing P. These shafts M M' are geared to the main-driving shaft N, which is carried in bearings in the same framing P as the said cam shafts, and the cams L are shaped so as to correctly apportion the time the fabric is to be under pressure, and the time required in which to feed the fabric forward, both operations being performed in one revolution of said shafts. As shown in the drawings, the cams L which act on anti-friction rollers B' on the bed B, are designed to raise and hold the bed B in its upper position for about half a revolution, and leave it at rest in its lower position for a like period.

20 The two cam-shafts M M' described are geared to the main driving shaft N of the press, as follows:—

One of said cam shafts M is connected to the main shaft N by means of toothed gearing disposed on said shafts, and two intermediate shafts Q and Q' mounted in bearings in the underframing P, and the other cam shaft M' is connected to the former by means of a driving chain R, and sprocket 30 wheels R' on the respective shafts.

The gearing for connecting the cam shaft M to the main driving shaft N, may be of any suitable arrangement, but is preferably of any well known variable speed type, so that the press can be driven at say three or any other, desired number of different speeds relatively to the main shaft N at will.

40 The fabric is fed over the board or plate C in the press, by rotating the horizontal rollers D D', and the vertical rollers G previously described for supporting said board, but in addition, two feed rollers K K' are provided at the rear of the press, between which the fabric is carried after it leaves the board C. A third roller K² is also provided behind the two former rollers. The whole of these rollers are rotated so as to feed the fabric forward in the interval between each pressing operation. In addition 50 the top feed roller K is raised when the feed is stationary, in order to obviate the marking of the work.

This is effected by mounting said roller K in two hand levers S, and disposing these 55 levers so that their inner ends rest on brackets on the lower rising and falling bed B. As a result, the levers S are raised each time the bed B rises to press the work carrying the roller K with them. These levers 60 S may be operated by hand in order to raise the roller K whenever it is desired.

The intermittent motion for effecting the 65 fabric feed, is obtained from the arrangement shown detached in Fig. 3. This comprises a toothed segment T, and a cam U,

both of which are mounted on the transverse cam shaft M, a pinion V mounted on an intermediate shaft W, and a spring actuated bell-crank pinion locking lever X, which is pivoted to the framing P. One end of the lever X is provided with a tooth X' to engage between the teeth of the pinion V, whilst its other end is engaged by the cam U. The toothed sector T as it moves round gears with the teeth of and rotates the pinion V through the requisite number of degrees, and then moves out of gear each motion, whilst the cam U acting on the lever X releases the pinion V just as the teeth of the sector T move into gear with it, and on the other hand releases the lever and permits it to lock the pinion the moment the sector moves out of gear.

The intermediate shaft W, is connected through the intermediary of a second shaft 25 Y, and chain and sprocket gearing, to the horizontal rollers K K' and K², the vertical rollers G geared to the transverse shaft H, and the horizontal rollers D and D' which support the board C, by means of chain and 30 sprocket gearing, so arranged that they all receive an intermittent fabric feeding motion from the first motion shaft W, of the correct velocity.

In feeding the fabric into the press, it is 45 in the arrangement shown in the drawings first fed over a stretching device Z of the same construction as described in the British Patent No. 212,369 hereinbefore cited. This first expands the fabric to the desired width, and delivers it on to the board or 50 plate C, after which it is fed along the said board or plate by the arrangement previously described.

The feed rollers used in connection with 105 the stretching device Z, as shown in Fig. 1^a and Fig. 2^a, may be intermittently rotated in the same manner and by the same means as those previously described, but this is not necessary, a continuous feed may 110 in this case be employed, and it is obtained by gearing all the said feed rollers to the cam shaft M' of the press, preferably by means of chain and sprocket gearing as 115 shown.

When this course is adopted, the work 120 fed forward over the device Z during the pressing operation of that part which is stationary on the board C, gathers for the time being on the ends of the arms F and the fore end of the board or plate C, and is then ready to be fed forward over the latter, the operation in this case being effected with less difficulty than if the fabric were taken straight from the device Z. An idle roller 125 may be provided above the end of the board C to prevent the gathered portion of the fabric from moving into the press before it is required.

With the arrangement described, not only 130

is there a great saving in labour owing to the operation being entirely automatic, but better results are obtained, for the simple reason that every length of the fabric receives exactly the same pressure, and it is subjected to such pressure and to the heat of the steam heated beds, for precisely the same period of time.

What we claim as our invention and desire to secure by Letters Patent is:—

- 10 1. In an automatic press for finishing tubular fabrics, a board or plate over which the fabric is fed disposed between the two beds of the press, rollers for holding said board or plate which also serve to feed the fabric forward, means for imparting intermittent feed motion to said rollers, and means for actuating the press so as to press the fabric in the intervals between the feeding movements, substantially as described.
- 15 2. In an automatic press for finishing tubular fabrics as claimed in claim 1, the herein described means for imparting an intermittent feed to the rollers in connection with the fabric extending board or plate disposed between the press beds, comprising

a toothed segment and a cam on the driving shaft, a pinion on the driven shaft, and a spring actuated lever for locking the pinion on the driven shaft which lever is operated by the cam on the driving shaft so as to release the pinion when the toothed sector moves into gear and lock it as the toothed sector moves out of gear, substantially as described.

3. In an automatic press for finishing tubular fabrics as claimed in claim 1, a press with an upper bed which is held down by springs and a lower bed which is raised and lowered by means of pairs of cams on two transverse cam shafts disposed under the lower bed said cams being so formed as to apportion the time the lower bed is in its respective upper and lower positions as is required to give the proper time for the feeding forward of the tubular fabric on the one hand and the pressing of it on the other hand, substantially as described.

In witness whereof we have hereunto set our hands.

GEORGE HUNT.

CHARLES WILLIAM CAMPION.
